UNITED STATES PATENT OFFICE.

THOMAS A. BLAKELY, OF FLESHERTON, CANADA, ASSIGNOR OF ONE-HALF TO FREDERICK W. HARRISON, OF OWEN SOUND, CANADA.

ANTIFRICTION-BEARING.

No. 800,789.

Specification of Letters Patent.

Patented Oct. 3, 1905.

Application filed May 16, 1905. Serial No. 260,728.

To all whom it may concern:

Be it known that I, THOMAS ALBERT BLAKELY, of the village of Flesherton, in the county of Grey and Province of Ontario, Canada, have invented certain new and useful Improvements in Antifriction-Bearings; and I hereby declare that the following is a full, clear, and exact description of the same.

This invention relates to an antifriction-bearing for a shaft or axle in which the bearing-rollers are preferably spaced and maintained in correct alinement by antifriction spacing means consisting of spacing-balls or spacing-rollers positioned to engage the trunnions of the bearing-rollers and maintained in contact therewith by bearing-rings contained within the journal-box.

For a full understanding of the invention reference is to be had to the following description and to the accompanying drawings, in which—

Figure 1 is a perspective view of a section of a line-shaft, journal-box, and the antifriction-bearing. Fig. 2 is a longitudinal sectional view of the construction shown in Fig. 1. Fig. 3 is a transverse sectional view of the construction shown in Fig. 1. Fig. 4 is a perspective view of the construction shown in Fig. 1 with part of the bearing-rings removed to illustrate the arrangement of the bearing-rollers and spacing means. Fig. 5 is a similar view to Fig. 3, showing antifriction-balls used as the spacing means.

Like letters of reference refer to like parts throughout the specification and drawings.

The journal-box is composed of two sections *a* and *a'*, having flanges *b* and *b'*, respectively, with alining bolt-holes *c* for the clamping-bolts *d*, by which the sections *a* and *a'* are securely fastened together to form the journal-box. Contained within the box are two bearing-rings *e* and *e'*, each composed of two separable sections having flanges *f* and alining bolt-apertures for the fastening-bolts *g*, which securely lock the bearing-ring sections together. The flanges *f* are contained in flange-seats *h* within the journal-box and journal-box flanges, so that when the journal-box sections are fastened together they will engage the bearing-ring flanges and hold the bearing-rings immovable in their fixed position. Each of the bearing-rings *e* and *e'* consists of a rim *i* and a side plate *j*, having a bore alining with the bore of the journal-box

for the line-shaft *k*. Encircling the line-shaft *k* between the bearing-rings *e* and *e'* are antifriction-rollers *l*, the ends of which are slightly removed from the inner edges of the bearing-ring rims *i*, and projecting within the rims *i* are the bearing-roller trunnions *m*, the ends of which are slightly removed from the side plates *j*, so that each bearing-roller may creep for a limited distance longitudinally in each direction and be prevented from binding against the bearing-rings during its individual revolution around its own axis or the collective revolution of all the bearing-rollers around the axis of the shaft. To maintain the correct alinement and spacing of the bearing-rollers, antifriction spacing means *m'* are interposed between the trunnions *m*. As shown in Figs. 1, 2, and 3, these antifriction spacing means consist of spacing-rollers of a shorter length than the length of the trunnions and of such a diameter that they will contact the trunnions and hold the bearing-rollers correctly spaced under all conditions of load and action, and, as shown in Fig. 5, the antifriction spacing means consists of spacing-balls *m''*, engaging the trunnions similarly to the spacing means shown in the previously-mentioned figures.

The rims of the bearing-rings prevent the radial displacement outward of the bearing-rollers and antifriction spacing means by engaging the bearing-roller trunnions and spacers, while the radial displacement inward of the bearing-rollers and spacing means is prevented by their contact with the line-shaft, and the longitudinal displacement of the bearing-rollers is limited by the contact of the bearing-roller ends against the inner edges of the bearing-ring rims, while the longitudinal displacement of the spacing means is limited by the bearing-ring side plates and the bearing-roller ends. The revolution of the line-shaft causes the independent revolution of each bearing-roller around its own axis and the collective revolution of the bearing-rollers around the axis of the line-shaft, so that the wear will be evenly distributed to each bearing-roller and to each part thereof, and to reduce the friction the bearing-rings are spaced so that the bearing-rollers will be free to move longitudinally in each direction between them, so that should either end of any or all of the bearing-rollers contact the edge of the adjacent bearing-ring rim such bearing-roller or

bearing-rollers will move in the opposite direction to clear it or themselves of contact therewith.

Having thus fully described my invention, 5 what I claim as new, and desire to secure by Letters Patent, is—

An antifriction-bearing comprising a journal-box having a longitudinal bore therethrough and composed of two separable sections having projecting flanges with alining apertures and fastening-bolts to extend through said apertures and fasten the separable sections together, said journal-box sections and flanges having within their inner 15 faces recesses, sectional bearing-rings composed of annular rims and side plates with longitudinal bores alining with the bore of the journal-box and flanges with alining bolt-apertures and fastening-bolts passing through 20 said apertures to fasten the bearing-ring sections together, the bearing-ring flanges being located within the journal-box recesses so that

the revolution of the bearing-rings may be prevented, bearing-rollers arranged in an annular set between the bearing-rings and of 25 such a length as to have a limited longitudinal movement in each direction between them, there being trunnions for the ends of the bearing-rollers contained within the bearing-ring rims, and antifriction-spacers contained within 30 the bearing-ring rims interposed between the bearing-roller trunnions, the edges of the bearing-ring rims being opposed to the bearing-roller ends to limit the longitudinal movement of the bearing-rollers in each direction, the 35 longitudinal movement of the antifriction-spacers being prevented by the bearing-ring side plates and bearing-roller ends.

Flesherton, May 8, A. D. 1905.

THOS. A. BLAKELY.

In presence of—

M. K. RICHARDSON,
Wm. H. BUNT.
